ONE-PIECE SUIT

Horace E. Shikles, Jr., Kansas City, Mo.

Application March 6, 1942, Serial No. 433,534

1 Claim. (Cl. 2-78)

This invention relates to garments and more particularly to one-piece suits for athletic and play wear, the principal object of the present invention being to provide a suit of this character that is constructed in such a manner as to allow free body movements of the wearer without binding and thereby enhancing the wearer's comfort.

Other objects of the invention are to provide a garment structure capable of being produced at lower cost and with less material than in garments of the same general character heretofore manufactured; to provide a garment of attractive appearance wherein any color scheme or trimming may be carried out in the parts making up the body of the garment; to provide a garment structure that is inherently adjustable to several sizes and in variable directions so that a manufacturer need make and stock fewer sizes; and to provide improved elements and arrangements thereof in garments of the character and for the purposes set forth.

In accomplishing these and other objects of the invention, I have provided improved details of structure, the preferred forms of which are illustrated in the accompanying drawings, wherein:

Fig. 1 is a perspective view of a garment embodying the features of the present invention as it appears upon a wearer.

Fig. 2 is a front elevational view of the garment showing the front shoulder strap disengaged from the shoulder tab to facilitate donning of the garment.

Fig. 3 is a horizontal cross-section through the garment on the line 3-3, Fig. 2.

Fig. 4 is a similar section on the line 4-4, Fig. 2.

Fig. 5 is a perspective view of a portion of the interior of the garment illustrating attachment of hip pads therein.

Fig. 6 is a front elevational view of a modified form of the invention.

Referring more in detail to the drawings, and first to the form of the invention illustrated in Figs. 1 to 5 inclusive:

1 designates a garment or suit such as may be worn by basketball players and which comprises a shirt portion 2, and a trunks or pants portion 3 interconnected with the shirt portion by elastic waist elements 4 and 5 which cooperate with similar elastic side elements 6 and 7 to promote flexibility of the garment.

The shirt portion 2 may be formed of any suitable cloth fabric woven with sufficient tightness

to maintain the shape and cut of a front 8 and a back 9. The lower or waist edges 10 and 11 of the front and back terminate above the waist line and extend substantially parallel therewith. The side edges 12-13 and 14-15 extend upwardly from the terminals of the edges 10 and 11 and join under the arms with arcuate edges 16 of the front and back portions to provide armholes 18 and 19. The upper portion of the front is cut downwardly and arcuately across the chest, as at 20, to provide shoulder straps 21 and 22. The upper portion of the back is cut with a larger arc 23 to provide shoulder tabs 24 and 25 adapted for connection with the shoulder straps 21 and 22 of the front 8 to complete the neck opening 26. One of the straps, for example 21, may be permanently stitched to the corresponding tab 24 of the back but the other shoulder strap is provided with suitable fasteners such as snaps 27 engageable with snaps 28 on the shoulder tab 25.

The pants portion 3 of the garment also includes a front 29 and a back 30. The front and back are preferably formed of pieces of fabric cloth 31-32 and 33-34.

The front pieces 31 and 32 are substantially alike and so shaped to have adjacent edges 35 and 36 joined together by suitable stitching 37 at the lower portions thereof and their upper portions above the stitching shaped to formlapping flies 38 and 39, secured together by suitable fastening means such as buttons, zippers, or the snaps 40, illustrated in the drawings. The opposite or outer side edges 41 and 42 align with the side edges 12 and 13 of the front 8, while the upper edges 43 terminate short of the waistline to accommodate the elastic waist section or element 4 previously mentioned. The lower portions of the front pieces are cut at the outer corners on arcs 44 extending from the terminals of the side edges to form crotch portions 45.

The back pieces are similarly shaped to provide a median seam formed as a continuation of the stitching 37 and side edges 46-47 aligning with the side edges 14 and 15 of the back 9. The upper edges terminate short of the lower edge of the back 9 to accommodate the waist element 5 and the lower portions are cut similarly to the lower portions of the front pieces to be joined with the crotch portions 45 thereof by suitable stitching indicated at 48.

The materials from which the front and back of the shirt and pants portions are formed are dependent upon the character of the suit. For example, a basketball suit ordinarily is composed

of satin or a similar closely woven fabric, while the corresponding parts of other types of play suits, such as baseball suits, swimming suits, unionalls, gym suits and the like, may be formed of softer and more loosely woven material. Combinations of loosely and tightly woven materials may be used, if desired, in order to give the desired service for which a particular garment is constructed. Seldom is there sufficient elasticity in the conventional garments to provide freedom of body movement without causing the garment to bind or draw across the body of the wearer. Consequently, to provide a smartly fitting garment provision is made herein for elasticity in the shirt and pants portions as well as in the connecting portions thereof. This is preferably carried out effectively by means of the elastic waist and side elements above mentioned.

The waist elements 4 and 5 are preferably formed of knitted material in such a manner as to provide wales or ribs 48 extending in one direction to limit elasticity in that direction and to provide elasticity transversely thereof. Since elasticity must be provided in the garment in a longitudinal or vertical direction to prevent binding of the crotch and limiting muscular movement of the body as when the athlete is reaching, bending over, or otherwise moving the body at the waist, the wales or ribs in the waist elements extend in a direction circumferentially of the waist as shown in Figs. 1 and 2.

The elastic waist elements have upper and lower edges 49 and 50 stitched as at 51 and 52 to the adjacent edges of the front and back sections of the shirt and pants portions of the garment, the waist elements being of a length corresponding to the width of the cloth forming the shirt portion. The side elements 6 and 7 are also formed of knitted material with the wales or ribs 53 extending vertically between the arm openings of the shirt portion and the leg openings of the pants portions, the side edges 54 and 55 of which are secured to the adjacent side edges of the pants and shirt portions and to the terminal ends of the front and back waist elements by lines of stitching 56.

The side elements thus provide for elasticity of the garment circumferentially thereof and permit a substantially trim fit on the wearer, at the same time cooperating with the waist elements in affording freedom of movement for the wearer.

In order to provide a finish and trim for the garment around the neck, arm and leg openings, the edges are piped with a flexible binding 57 secured by a flexible stitching. For appearance the binding may have a color different from the other portions of the garment.

The waist and pants portions, as well as the elastic waist and side elements may be of different colors thereby providing further ornamentation.

If desired, the waist portion of the completed garment may be provided with a series of loops 58 through which a belt 59 or the like may be extended as shown in Fig. 1.

In applying the garment constructed and assembled as described, the shoulder strap 22 is disengaged from the tab 25 and the wearer steps through the opening formed by the neck and left side arm opening so that the feet and legs pass through the respective leg openings of the pants portion. The garment is then pulled upwardly over the trunk of the body so that the right arm

may be extended through the right arm opening 18 of the garment. The shoulder strap 22 is then secured over the shoulder of the other arm 25 by engaging the snaps 27 and 28.

5 In case of a basketball suit, it may be desirable to provide the pants portion with hip pads 69 such as shown in Fig. 5, in which case the upper edges of the pads 69 are suspended by means of tapes 61, 62 and 63, the tapes 61 and 63 10 being attached to the upper corners of the pad and secured to the adjacent ends of the waist elements 4 and 5 by stitching 64, while the tape 62 is attached at the central portion of the upper edge of the pad and to the elastic side elements by 15 similar stitching as illustrated in Fig. 5. The pads when thus attached hang freely and do not interfere with the elasticity of the garment.

In the form of the invention illustrated in Fig. 6, the front and back 65 and 66 of the shirt portion 67 are cut so that the side edges 68 may be joined by seams extending downwardly from the arm openings. The front and back of the pants portion 69 are formed in the same manner as the corresponding portions of the form of the invention illustrated in Figs. 1 to 5 inclusive. The shirt and pants portions 67 and 69 are joined together by a continuous elastic band 70 extending circumferentially of the waist so as to provide elasticity across the wales and to limit circumferential elasticity to retain the shape of the garment under movements of the wearer. Circumferential elasticity is provided in the pants portion by elastic inserts 71 and 72 corresponding to the elastic side elements previously described. 35 These inserts have their upper ends 73 secured to the lower edge of the band 70 as clearly shown in the drawings. This construction provides for freedom of movement of the wearer for the reason that strains in the shirt portion are compensated for through bias stretch of the waist band.

While I have particularly illustrated and described a basketball suit, it is obvious that the invention is adapted to baseball, swimming and other types of play suits without departing from the spirit of the invention.

From the foregoing it is obvious that I have provided a one-piece garment or play suit especially adapted for athletic use and which is constructed so that it accommodates itself to movements of the wearer and yet maintains the trim shape thereof. It is also obvious that the structure particularly adapts the garment to various color combinations desired in athletic suits.

55 What I claim and desire to secure by Letters Patent is:

An outer garment for wear during playing of games and adapted to closely fit the wearer without binding including, front and back shirt portions of non-elastic fabric extending from the top to the waist of the garment, spaced straps connecting said shirt portions forming neck and arm openings, bindings of knitted fabric around said neck and arm openings, strips of elastic fabric having vertically arranged wales, the side edges of said strips being connected to the side edges of said shirt portions, said strips having substantial elasticity circumferentially of the garment, front and back pants portions of non-elastic fabric extending from the bottom of the garment to the waist thereof, the central portion of the lower edges of said pants portion being connected to form a crotch, said front pants portion having a fly therein, the lower edges of said pants portion being cut at the sides of the crotch

portion to form leg openings, strips of elastic fabric having vertically arranged wales, the side edges of said second named strips being connected to the side edges of said pants portion and having substantial elasticity circumferentially of the garment, an elastic waist strip having circumferentially arranged wales and substantial elasticity across said wales, the side edges of said strip being connected to the upper and

lower edges of the pants and shirt portions and the elastic strips therein respectively, said waist strip extending continuously circumferentially of the garment and across the fly of said front pants portion to provide vertical stretch to the garment, and bindings of knitted fabric around the leg openings.

HORACE E. SHIKLES, JR.
